UNITED STATES PATENT OFFICE.

CHARLES H. WHITE, OF GLENWOOD SPRINGS, COLORADO, ASSIGNOR OF ONE-THIRD TO
FRANK W. GOODRICH, OF GLENWOOD SPRINGS, COLORADO.

MAIL CATCHING AND DELIVERING MEANS.

1,255,371.

Specification of Letters Patent.

Patented Feb. 5, 1918.

Application filed September 27, 1916. Serial No. 122,457.

To all whom it may concern:

Be it known that I, CHARLES H. WHITE, a citizen of the United States, residing at Glenwood Springs, in the county of Garfield and State of Colorado, have invented 5 certain new and useful Improvements in Mail Catching and Delivering Means, of which the following is a specification.

This invention relates to mail catching 10 and delivering means, and more particularly to means for removing a bag of mail from a support or rack and for simultaneously delivering a bag of mail.

One of the main objects of the invention 15 is to provide a receiving and delivering means of simple construction and operation. A further object is to provide a rack and a hook, the hook and rack being provided with coöperating means for delivering a bag of 20 mail to the rack and for simultaneously removing a bag of mail supported by the rack. A further object is to provide means of simple construction and operation for supporting a mail bag. A still further object is to 25 provide simple and efficient means for delivering and receiving a mail bag. Further objects will appear from the detailed description.

In the drawings:

30 Figure 1 is a front view of the delivering and receiving rack,

Fig. 2 is an end view of the rack and the hook in operative position,

Fig. 3 is a top plan view of the receiving 35 and delivering hook,

Fig. 4 is a back view of the same,

Fig. 5 is a top plan view of the modified form of hook,

Fig. 6 is the same partly in section,

40 Fig. 7 is a section on line 7—7 of Fig. 5,

Fig. 8 is a section on line 8—8 of Fig. 3,

Fig. 9 is a detail of the mail receiving hook supporting rod,

Fig. 10 is a section on line 10—10 of 45 Fig. 9,

Fig. 11 is a section on line 11—11 of Fig. 5,

Fig. 12 is a section on line 12—12 of Fig. 3, and

50 Fig. 13 is a detail of the mail bag receiving trough.

The front and back plates 1 and 2, respectively, are supported in parallelism by the corner posts 3. These plates are secured 55 together and braced by cross beams 4, 5, and

6. Two U's 7 and 8 are supported by the front plate, near each end thereof. These U's are provided with uprights 9, the upper ends of which are secured in brackets 10 which are fastened to the under face of a 60 horizontal channel bar 11. This bar is provided, through its upper side, with a central longitudinal slot 11^a and is adapted to slidably receive a block 12 provided with a 65 snapple 13. Mounted on the back plate 2 there are three U-members 14, 15, and 16. These members each support a goose-neck 17. These goose-necks are secured in brackets 18 fastened on the upper face of a channel bar 19 similar to the bar 11 and serves 70 to support this bar in vertical alinement with the same. The upper bar 19 is adapted to slidably support a block and snapple similar to that mounted in the lower bar, and these two snapples receive the rings at 75 the ends of the mail bag 20 so as to removably support the same in the rack.

Mounted in back of the channel bars are two oppositely inclined tripping rods 21. These tripping rods are supported by end 80 standards 22 secured to the intermediate cross beams 23, and by a central brace 24 secured through the central cross beam 5. The tripping rods have their inner ends connected by a T 26 secured thereto and to the 85 upper end of the brace 24. This T is positioned at the longitudinal center of the channel bars, and the tripping rods are positioned in back of and between the channel bars, for the purpose to be later disclosed. 90

The goose-necks 17 are braced by hook members 27 passed about the same carried by a horizontal bar 28 which is supported by standards 29 mounted on the intermediate cross bars 23, near the upper ends thereof 95 which are extended beyond the back plate 2 for this purpose. The goose-necks are further braced and secured in spaced relation by the horizontal brace rods 28^a which are secured in T-joints 28^b secured at the 100 center of the horizontal arms of the goose-necks and a four-armed joint 28^c secured at the center of the horizontal arm of the central goose-neck. This serves to securely brace and rigidly support the goose-necks so 105 as to secure the upper channel bar 19 in proper position relatively to the lower bar 11.

At the front of the rack, below and in front of the channel bars, is mounted a re- 110

ceiving trough or basket 30. This basket is supported by three U-brackets 31, each formed with a goose-neck 32 which is secured through the front plate 1. Each side 5 wall of the basket is provided, near each end, with a vertical groove 31^a. These grooves are in alignment transversely of the basket and are adapted to slidably receive an end gate 33. This gate is mounted in 10 one end of the trough or basket so as to retain the mail bag delivered into the same from a passing train, which end depending on the direction of travel of the train.

For convenience in placing the bag in the 15 rack so as to be grasped by the hook of a passing train, the rack platform or base is provided, at each end, with suitable steps 34. It will, of course, be evident that the base or support for the rack can be constructed in 20 any suitable manner desired, the only requirement being that there be means for properly bracing and supporting the various uprights and braces for the goose-necks and tripping rods, and the channel bars.

25 For use in connection with this delivering and receiving rack, I have provided a hook of special construction adapted to coöperate with the tripping rods and supporting channel bars so as to receive or remove the mail 30 bag from between the same, and to be simultaneously actuated by the tripping rods so as to deliver a bag of mail into the receiving trough or basket 30. This hook is illustrated in Figs. 3 and 4 of the drawings.

35 The hook 35 is of rectangular shape being provided with the end bars 36 and 37 and a back bar 38, all integrally connected to form a quadrilateral, the front of which is open. An arm 39 is secured to the front end 40 of the end bar 36 of the hook. The inner end of this arm is secured to a vertical bar 40 by means of a four-armed joint 41. This bar is 45 slidable between sheaves 42 adapted to be secured to the side beam of the door frame of a mail car in the usual manner. The bar 40 is provided with spaced limiting bolts 43 threaded therein adapted to engage with the slots 44 and 45 in the sleeves 42. By means of a handle 46 the bar 40 may be adjusted 50 so as to secure the arm 39 in a position at right angles to the side of the car, in the usual manner. In this position the hook 35 projects from the car A in a horizontal plane such a distance as to pass between the channel bars 11 and 19 of the rack so as to engage the mail bag 20 supported thereby at the restricted center of the same, as in Fig. 2 of the drawings.

The hook is provided with two opposed 60 gripping jaws 47 and 48 which form an approximate ellipse to receive the central portion of a mail bag. The jaw 47 is secured to the front end of the outer end bar 37 of the hook by means of a spring shank 49 formed integral therewith. The jaw 48 is

similarly secured to the front end of the bar 36 by a shank 50. The gripping jaw 47 is further provided with a resilient spring member 51 of approximately S-shape which is secured thereto and to the inner face of 70 the outer end bar 37. The gripping jaw 48 is similarly reinforced by a resilient member 52.

The space between the inner ends of the shanks 49 and 50 is of somewhat less width 75 than the width of the restricted central portion of the mail bag 20. When the hook engages the mail bag the central portion of the bag is forced between the shanks 49 and 50 into an approximately elliptical space between the gripping jaws 47 and 48. The impact of the hook with the mail bag is sufficient to force the jaws apart so as to permit entry of the bag between the same. As soon as the bag enters between the two jaws, the 80 resilient shanks 49 and 50, and the spring members 51 and 52 act to force the two jaws together so as to firmly grip the bag and hold it in the hook. When the bag has been gripped in this manner by the hook it is 85 forced longitudinally of the supporting channel bars 11 and 19 so as to be removed from the same, by the forward travel of the train. As soon as the bag has been 90 completely removed from the rack, the rod 40 is operated by means of the handle 46 so as to swing the hook and the bag carried thereby into the car door, in the usual manner. The mail bag 20 is supported at the ends of the channel bars in the direction in which the 95 train approaches the station. This will be clear from Fig. 1 of the drawings, in which it is assumed that the train is traveling from the left hand end of the rack toward the right hand end, as viewed in the drawings. 100

A lever arm 53 is pivotally mounted on the back bar 38 of the hook 35. This arm is provided with a central polygonal aperture 54 which snugly receives the polygonal outer portion 55 of a pivot bolt 56 which is 105 mounted in an aperture through an enlarged portion 38^a of the back bar 38. The inner end of this bolt is threaded to receive a securing nut 57 which is locked in position by a cotter pin 58 passed through the bolt. An 110 oil duct 59 communicates with the aperture which receives the bearing portion of the bolt 56 so as to permit a suitable lubricant to be injected into the same, in the usual manner. 115

The outer portion of the arm 53 is reduced and rounded, as at 60, and a sleeve 61 is loosely mounted thereon. This sleeve is retained in position by a nut 62 secured on the outer threaded end of the reduced portion 120 60 of the arm. The inner end of the arm is reduced to form a flat inwardly extending member 63. This member is apertured, as at 64. The back member 38 of the hook is provided with a transversely extending re- 125 130

cess 65 below the member 63. A T-bolt 66 is secured through the cross bar with its head in the recess 65. A rectangular plate 67 has its inner end bifurcated to form lateral arms 68 which are bent about the arms of the head 69 of the T-bolt so as to loosely connect the plate to the back bar 38 of the hook 35. The outer end of this plate is similarly bifurcated to support a transverse pin 70. A link 71 is loosely mounted on the pivot pin 70 and is inserted through an eye 72 which is loosely secured through the head of a tapered pin 73. This pin is adapted to extend across the aperture 64 of the reduced portion 63 of the arm 53. When in operative position the head of the pin rests on the outer bar of the member 63 and the point rests on top of the inner bar. This brings the eye 72 in engagement with the upper outer corner of the outer bar of member 63 so that, when the arm is rocked about its pivotal axis so as to raise the member 63, the pin 73 will be drawn off of the said member, by means of the plate 67, link 71, and eye 72.

25 The pin 73 is adapted to be inserted through a ring or loop 74 on the end of the mail bag 75 which it is desired to deliver. As the hook 35 passes between the channel bars 11 and 19 of the delivering and receiving rack so as to engage the mail bag 20 supported thereby, the sleeve 61 of arm 53 engages one of the tripping rods 21 so as to rock the outer end of the arm downward and raise the inner end or reduced portion 63 thereof. This results in releasing the mail bag 75 which drops into the receiving trough 30, being retained therein by the end gate 33. The hook 35 removes the bag 20 from the rack and, simultaneously therewith, delivers the bag 75 into the receiving trough 30. By this means the receiving and delivering rack and hook coöperate to remove a bag of mail from the rack and to simultaneously deliver a bag of mail.

45 At the inner end of the back bar 38 of the hook 35, at the top and bottom thereof, are secured buffer springs 76 and 77 of laminated construction, respectively. These springs are adapted to be engaged by the reduced portion 63 of the arm 53 when it is rocked about its pivotal axis so as to limit movement of the same. The recess 65 of the back bar 38 is of such depth that the head of the T-bolt 66 does not project beyond the outer face of the bar. By this arrangement the plate 67 and the elements carried thereby can be placed in operative position about the member 63 of the arm 53 from either side of the arm. This renders it possible to releaseably suspend a mail bag from the hook 35 regardless of the direction of travel of the train. Also, by providing two oppositely inclined tripping rods 21, the arms 53 will be tripped with the train traveling in either direction so that the hook and rack are

adapted to coöperate so as to simultaneously receive a mail bag from, and deliver a mail bag to, a train traveling in either direction.

In the modified form of hook shown in Figs. 5, 6, and 11 of the drawings, the gripping jaw 48 is replaced by a resilient jaw 48^a connected by the shank 50^a to the head 50^b of a T-bar 78. This bar is slideable in a casing 79 secured on an integral extension 80 of the inner end bar 81 of the head. A coil spring 82 is mounted in the casing 79 and acts to normally force the T-bar 78 inward. A spring pressed latch 83 is mounted on the end bar 81 and engages a recess in the T-bar so as to normally hold the same in outward position. This latch is connected by a chain 84 which passes through eyes 85 to a block 86 fixedly secured on the inner end of the pivot bolt 56^a which is rotatably mounted in the bearing strap 56^b secured to the top of the back bar 38^a of the head. When the arm 53 is rocked about its pivotal axis, the pivot bolt 56^a is rotated and acts, by means of chain 84, to retract the latch 83 so as to release the T-bar 78. The T-bar is forced inward by means of the coil spring 82 so as to firmly grasp the mail bag and hold the same in the hook. When it is desired to release the mail bag the T-bar 78 is forced outward, by means of the knob 87 secured therein and projecting through the slot 88 in the casing 79. When withdrawn into inoperative position, the T-bar is held in this position by the latch member 83, as in Fig. 6 of the drawings. The operation of this hook in receiving and delivering a bag of mail is the same as that of the hook shown and described above, and the hook shown in Figs. 5, 6, and 11 of the drawings, is merely intended to illustrate a modification or variation thereof.

It will be evident that certain changes can be made in the construction and arrangement of the various parts of my invention without departing from the field and scope of the same, and I intend to include all such variations as fall within the scope of the appended claims, in this application in which a preferred form only of my invention is disclosed.

What I claim, is:—

1. In a mail delivering and receiving means, a hook adapted to engage a bag of mail, an arm pivotally mounted on the hook and having its outer end projecting beyond the hook and adapted to engage tripping means, a pin engaging the inner end of said arm and adapted to support a bag of mail, and means for moving the pin into inoperative position when the arm engages tripping means so as to cause it to be rocked about its pivotal axis.

2. In a mail delivering and receiving means, a hook adapted to engage a bag of mail, an arm pivotally mounted on the hook and having its outer end projecting beyond

105

110

115

120

125

130

the hook, a pin engaging the inner end of said arm and adapted to support a bag of mail, and a plate pivotally connected at its inner end to the inner end of the back bar 5 of the hook and loosely connected at its outer end to the pin.

3. In a mail delivering and receiving means, a hook provided with opposed resilient gripping members adapted to engage 10 a bag of mail, an arm pivotally mounted on the hook and having its outer end projecting beyond the hook, a pin engaging the inner end of said arm and adapted to support a bag of mail, and means for removing the 15 pin into inoperative position when the arm is rocked about its pivotal axis.

4. In mail bag receiving and delivering means, a rectangular hook, a pair of opposed inwardly directed gripping jaws 20 mounted on said hook in spaced relation and provided with resilient shanks secured to the front of said hook at each side thereof whereby said jaws may be forced apart so as to receive and grip a mail bag, and a resilient reinforcing member interposed between each of said gripping jaws and the adjacent arm of the hook so as to reinforce said jaws and hold the same in tight gripping 25

engagement with a mail bag forced therebetween.

5. In mail bag receiving and delivering means, a rectangular hook having a back bar and a side bar at each end thereof and disposed substantially at a right angle to the back bar, opposed approximately semi-elliptical inwardly directed gripping jaws 30 mounted on said hook and each provided with an integral resilient shank secured to the forward end of the adjacent end bar of said hook, an arm rockably mounted intermediate its ends on the back bar of the hook on a horizontal axis and extending beyond the outer side bar of the hook, the said arm being vertically apertured adjacent its inner end, a pin adapted to extend across said 35 aperture so as to be supported on the upper face of said arm, and connections between said pin and hook for withdrawing the pin from the arm when the outer end of said arm is depressed.

In testimony whereof I affix my signature in presence of two witnesses.

CHARLES H. WHITE.
